UNITED STATES PATENT OFFICE.

MAYNE C. P. PARKER, OF NICHOLSON, PENNSYLVANIA.

TOY GUN.

Application filed August 25, 1924. Serial No. 734,017.

To all whom it may concern:

Be it known that I, MAYNE C. P. PARKER, a citizen of the United States, residing at Nicholson, in the county of Wyoming and 5 State of Pennsylvania, have invented certain new and useful Improvements in Toy Guns; and I do hereby declare the following to be a full, clear, and exact description of the invention, such as will enable others 10 skilled in the art to which it appertains to make and use the same.

This invention relates to an improved sounding toy, and more particularly to a toy gun for children which will make a 15 sharp sound or report whenever the trigger of the gun is manipulated.

An object of the invention is to provide an improved sounding toy and more particularly a toy gun which will be so constructed that it will have a tongue adapted to be engaged and suddenly released by the trigger, and a recessed sounding chamber positioned in the stock of the gun so that the noise will be considerably amplified.

25 A further object of the invention is to provide an improved form of toy gun which may be made of wood, fibre, or metal, and which will be highly efficient in use and quite inexpensive to manufacture.

30 Other objects will appear as the description proceeds.

In the accompanying drawings which form a part of my application,

Fig. 1 is a side elevation of my improved 35 toy gun.

Fig. 2 is a partial sectional view through the stock and a portion of the barrel of my improved toy gun, showing the same provided with a single reed or sounding tongue.

40 Fig. 3 is a vertical sectional view through the stock and a portion of the barrel of the gun showing a double reed or tongue construction.

Fig. 4 is a horizontal sectional view taken 45 on the line 4—4 of Fig. 2; and

Fig. 5 is a sectional view taken on the line 5—5 of Fig. 2.

Like characters of reference are used throughout the following specification and 50 the accompanying drawings to designate corresponding parts. My improved toy gun consists of a barrel 1 and a stock 2 which is suitably attached to the barrel by means of the screws 3. A sight 4 is positioned on 55 the upper surface of the barrel 1 adjacent

the forward end thereof as clearly illustrated in the drawings.

The stock 2 is cut out from the bottom thereof or recessed to form a sounding chamber 5 which is substantially inverted U-shaped in cross section as illustrated in Fig. 5 of the drawings. This construction provides for the spaced oppositely disposed sounding walls 6 which serve to increase the sound made by the gun, as will more clearly 65 be described later on.

In Fig. 2 of the drawings I have illustrated a single reed or sounding tongue 7 which is adapted to be inserted in the end of the stock 2 and held in position by means of 70 the screws 8. The tongue 7 may be slightly tapered toward its free end or straight and is substantially flat and terminates adjacent the star wheel or trigger 9 which is pivoted on the pin 10, which in turn is mounted 75 transversely of the stock between the side walls 6. It will readily be seen that as the trigger 9 is rotated, the adjacent lower point of the same will force or flex the sounding tongue 7 upwardly until the said point slips 80 free from the end of the tongue, whereupon the sounding tongue will snap backward into its original position in contact with the next adjacent point. This snapping back of the tongue will produce a sharp noise or report, 85 which will be considerably amplified due to the presence of the sounding chamber 5 and the spaced sounding walls 6 of the stock. This operation may be repeated as often as desired, and every time the trigger is rotated 90 a partial turn the tongue will snap, consequently making a noise which will be highly pleasing to children playing with the gun.

In Fig. 3 of the drawings, I have illustrated a slight modification of my invention 95 which comprises a scheme of hollowing out or forming of the recess 5 in the stock, but in this type or modification a shoulder 11 is formed within the said chamber adjacent the rear end of the stock and serves as a support 100 for the spaced tongue members 12 which are suitably spaced by means of the washers 13 held in position by means of the screws 14. The same type of trigger 9 is employed in this modification and is mounted on a similar pin 10, as in the first mentioned type of gun. The operation of the modified form of gun is the same as in the first described gun, except that now the spaced sounding tongues are 105 both flexed upwardly by the trigger and when 110

they snap back the two tongues will sharply engage each other thereby producing a sound or report which will be considerably louder than that made by the first type of gun. In 5 this case the sounding chamber and spaced sounding walls will also considerably amplify the sound so that a very loud noise may be heard.

It will be readily apparent that slight 10 changes may be made in the construction of this toy, but it is thought that the broad idea of having the sounding tongue operated by a suitable trigger and positioned in a sounding chamber, and having the sounding boards 15 or walls 6 at either side of the tongue is new in the art.

Many minor changes in detail of construction may be resorted to without departure from the spirit of the invention.

I claim:

A toy gun comprising a barrel and interconnected stock, said stock being provided with an internal sounding chamber and spaced oppositely disposed amplifying walls or boards, a shoulder formed within said stock, spaced sounding tongues positioned on said shoulder, and a star wheel trigger adapted to flex said tongues upon rotation of the same to produce a distinct noise. 20 25

In testimony whereof I affix my signature.

MAYNE C. P. PARKER.
